CLAIM

The ornamental design for an apron front sink with outward angled apron as shown and described.

DESCRIPTION

FIG. 1 is a perspective view of the claimed design; FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; FIG. 7 is a bottom view of the claimed design shown in FIG. 1; and,

FIG. 8 is a cross-sectional view of the claimed design taken along line 8-8 in FIG. 2.

The ornamental design that is claimed is the upward angled configuration of the outwardly extending sink apron, as illustrated best in the cross-sectional view provided. The broken lines in the drawings show portions of the apron front sink with outward angled apron that form no part of the claimed design. Furthermore, FIG. 2 shows the line 8-8 in which the cross-sectional view of FIG. 8 is taken along in broken lines forming no part of the claimed design.
